inventor:
Max Marsack

UNITED STATES PATENT OFFICE

MAX MARSACK, OF SHEBOYGAN, WISCONSIN

MATTRESS

Application filed November 5, 1928. Serial No. 317,322.

My invention belongs to that general class of devices known as mattresses and particularly an inner spring mattress or mattress in which a spring construction is arranged within the mattress and enclosed by an exterior covering. The invention has among its objects the production of a mattress of the kind described that is comfortable, attractive, durable, efficient and satisfactory. 10 It has particularly as an object the production of a mattress provided with a quilted side boxing in which the boxing is not only connected at opposite sides of the mattress through the covering sheets or ticking but is 15 also connected by suitable connecting means and so arranged as to maintain the boxing taut and without buckling. In a mattress of this kind where a quilted side boxing is employed provided with inner and outer plies 20 with filling between, the mattress after continued use may become unattractive owing to the buckling or wrinkling of the side boxing. With the construction shown the boxing retains its shape at all times with a minimum of 25 buckling.

Many other objects and advantages of the construction herein shown and described will be obvious to those skilled in the art from the disclosure herein given.

30 To this end my invention consists in the novel construction, arrangement and combination of parts herein shown and described, and more particularly pointed out in the claims.

35 In the drawings, wherein like reference characters indicate like or corresponding parts:

Fig. 1 is a sectional view through a mattress illustrating my improved construction; 40 and

Fig. 2 is a section taken substantially on line 2-2 of Fig. 1.

Referring to the drawings, in which only one embodiment of the invention is shown, 45 a resilient spring construction or the like is provided consisting of the desired number of springs 1 enclosed in a cover 2. It should be understood that while one type of spring construction is shown, the spring construction in itself forms no part of my invention

and the same may be constructed in any other suitable manner. The mattress is made up with filling 3 of cotton felt, curled hair, kapock or any other material suitable for the purpose, and covered with the cover sheets 4 of suitable ticking. Around the edge of the mattress is arranged an edge boxing which consists of inner and outer plies 5 and 6 of suitable fabric between which is arranged filling 7, the inner and outer plies 5 and 6 and filling being secured together or quilted by means of eyelets 8 or the equivalents for the purpose. The edges of the inner ply 6 at one side or end of the mattress are connected to the edges of the inner ply of the 55 boxing, and the opposite side or end of the mattress by means of the straps 9 or the equivalent secured to the inner ply as indicated at 10 by stitching or in an equivalent manner. These tie members 9 or straps are 60 made of suitable material and in some instances may be made of elastic material if so desired. Generally, it is preferred not to secure the straps together where they overlap one another nor to secure them to the 65 spring construction. Obviously, the straps or members 9 are applied over the faces of the construction prior to the placing of the filling thereover, although in some instances, if 70 desired, the same may be extended over the filling. The edge portions 13 of the outer plies 5 are secured to the edge portions 12 of the cover sheets 4 by hemming or otherwise securing the same together as indicated at 75 14. Corner rolls 15 are formed about the mattress by stitching through the filling adjacent the cover sheet and ply edge 13 as indicated in 16. The mattress may be tufted 80 as indicated by the tufting loops 17 or in an equivalent manner.

85 A mattress constructed as described is not only particularly attractive and durable in appearance, but is economical in construction and, owing to the eyelets, a depression or expansion of the mattress does not cause the boxing to be bulged inwardly or outwardly. The straps 9 tend at all times to keep the boxing under tension and hold the same 90 substantially as shown in Fig. 1.

95 Having thus described my invention, it is 100

obvious that various immaterial modifications may be made in the same without departing from the spirit of my invention; hence I do not wish to be understood as limiting myself to the exact form, construction, arrangement and combination of parts herein shown and described or uses mentioned.

What I claim as new and desire to secure by Letters Patent is:

- 10 1. In a mattress of the kind described and in combination, an inner resilient construction provided with an enclosing casing, filling material arranged across opposite faces of said construction at the exterior of said casing, cover sheets extending across said filling material, a quilted side boxing consisting of a plurality of plies of fabric with filling material arranged therebetween and secured together, and tightly stretched cross bands forming a lattice structure on the opposite faces of said construction, the ends of said bands being fastened to the adjacent inner ply of said boxing, the edges of the outer ply of the boxing secured to the edges 25 of said cover sheet, stitching extending through the filler and connecting said ply and cover sheet at points spaced back from the junctures of the cover sheets and outer ply.
- 30 2. In a mattress of the kind described and in combination, an inner spring construction, filling material arranged over opposite faces of said construction at the exterior thereof, cover sheets extending over said filling material, a continuous quilted side boxing extending about the construction consisting of a plurality of inner and outer plies of fabric with filling material arranged therebetween and secured together, and tightly stretched cross bands forming a lattice structure on the opposite faces of said construction, the ends of said bands being fastened to the adjacent inner ply of said boxing, the edges of the outer ply of the boxing secured to the edges 45 of said cover sheet.
- 35 3. In a mattress of the kind described and in combination with an inner spring construction, a quilted side boxing having inner and outer plies, and means separate from the 50 spring construction for supporting the boxing consisting of tightly stretched cross bands forming a lattice structure on the opposite faces of said construction, the ends of said bands being fastened to the adjacent inner ply of said boxing.

In testimony whereof, I have hereunto signed my name.

MAX MARSACK.
